Application filed September 4, 1908. Serial No. 451,757. Term of patent 7 years.

To all whom it may concern:

Be it known that I, ZDENKO FREUND, a citizen of the United States, residing at Newark, in the county of Essex and State of New Jersey, have invented and produced a new, original, and ornamental Design for the Head of a Brooch, Scarf-Pin, or Similar Article; and I do hereby declare the following to be a full, clear, and exact description of the invention, such as will enable others skilled in the art to which it appertains to make and use the same, reference being had to the accompanying drawings, and to letters of reference thereon, which form a part of this specification.

Figure 1 is a front elevation illustrating my new design; and Fig. 2 is a side elevation of the same.

As shown in the drawings, the leading or

material feature of my design consists in an ornamental head for brooches, scarf-pins or similar articles, having at its front, the shape of a carnivorous animal's head, incased in a cage or muzzle.

In said drawings, *a* indicates an ornamental head of my new design having at its front the configuration of the head of a carnivorous animal. Surrounding and inclosing the head *a*, is a cage or muzzle *b*, mounted, as at *c*, upon the back *d* of the ornamental head *a*.

I claim:

The ornamental design for the head of a brooch, scarf-pin or similar article, as shown and described.

ZDENKO FREUND.
